INVENTOR.
BY *alfred Morris Thomson*
Cipriano Andrade, Jr.
ATTORNEY.

UNITED STATES PATENT OFFICE.

ALFRED MORRIS THOMSON, OF NEWARK, NEW JERSEY, ASSIGNOR TO JOSEPH MER-
CADANTE, OF NEW YORK, N. Y.

LUBRICANT SEPARATOR.

Application filed August 24, 1925. Serial No. 52,181.

In the prior art one of the chief difficulties in electrical refrigerators is that the necessary lubricant, used in the compression pump, becomes after a time split up into 5 very minute particles which are so small that they are carried bodily by the refrigerating fluid through the cooling coil and into the refrigerating system, and thereupon these minute particles of the lubricant be- 10 come congealed into much larger units and gradually stop up the various working parts of the refrigerating system.

My invention relates to lubricant separators to separate the lubricating oil from refrigerating fluid in electric refrigerators, and thus to avoid this gradual stopping up 15 of the refrigerating system.

I obtain this object by the mechanism illustrated in the accompanying drawings, in 20 which:

Fig. 1 is a sectional side-view of my applied device taken on section line 1—1 of Fig. 2; and Fig. 2 is a sectional end-view of my applied device taken on section line 2—2 25 of Fig. 1.

Similar letters refer to similar parts throughout the several views.

Q is a rotary pump operated by shaft Q¹. P is an air fan rotating with said shaft Q¹. 30 R is a housing, with fins S. E is the discharge end of housing R, and F is the bottom space of housing R. U is a tube for taking the refrigerating fluid from cooling coil T into rotary pump Q, and W is the outlet tube for the refrigerating fluid from housing R. B is the outlet tube from housing R for the lubricant. A is a cooling tube with fins F, which receives the lubricant from outlet tube B. C is a tube connecting 35 cooling tube A with cooling tube A¹, which has fins F¹. D is an outlet tube from cooling tube A¹ to the intake end of rotary pump Q. T is the cooling coil which receives the refrigerating fluid from outlet tube W.

The operation of my device is as follows:

Assume that rotary pump Q is in operation rotated by shaft Q¹, with air fan P also being rotated by shaft Q¹, and with a lubricant being drawn into pump Q through

tube D, and with the refrigerating fluid being drawn into pump Q through tube U. Rotary pump Q thereupon will discharge the lubricant and the refrigerating fluid under pressure into the inside of housing R, 55 as shown in space E. Thereupon the refrigerating fluid being in gaseous form and under pressure will work out through tube W and cooling tube T, and the lubricant being in liquid form and under pressure will drop 60 to space F, and will work out through tube B into cooling tube A. The circulating air driven by air fan P will cool tube A, and said cooling will be increased through fins F. From cooling tube A, the lubricant will 65 travel through tube C into cooling tube A¹, with fins F¹ where the cooling of the lubricant will be further increased. From cooling tube A¹ the lubricant will be drawn through tube D into the suction end of rotary pump Q. By reason of this cooling process the lubricant, which otherwise would have been left in minute particles, is reduced once more to its normal liquid condition, and enters rotary pump Q as a normal 70 flowing liquid.

It will be understood that fins F and F¹ might be omitted, or that the cooling of tubes A and A¹ might be effected through cooling water or other cooling means, without departing from the essential elements of my invention.

I claim—

1. A lubricant separator comprising a pump, a refrigerating fluid and a lubricant operated on by said pump, a housing surrounding said pump, an outlet adapted to discharge said refrigerating fluid from said housing, another outlet adapted to discharge said lubricant from said housing, cooling means adapted to receive said lubricant and cool the same, and an outlet from said cooling means adapted to discharge said lubricant from said cooling means into the intake end of said pump.

2. A lubricant separator comprising a pump, a refrigerating fluid and a lubricant operated on by said pump, means for discharging said refrigerating fluid from said pump, separate means for discharging said

95

100

lubricant from said pump, means for receiving and cooling said lubricant, and means for conducting said lubricant from said cooling means to said pump.

5 3. A lubricant separator comprising a pump, a refrigerating fluid and a lubricant operated on by said pump, means for discharging said refrigerating fluid from said

pump, separate means for discharging said lubricant from said pump, a cooling tube 10 with fins adapted to receive said lubricant, an air fan adapted to cool said cooling tube, and means for conducting said lubricant from said cooling means to said pump.

ALFRED MORRIS THOMSON.
